(57) **CLAIM**

The ornamental design for an electronic device with a tablet stand, as shown and described.

DESCRIPTION

FIG. 1 is a front, right, perspective view of an electronic device with a tablet stand.

FIG. 2 is a front view of the electronic device of FIG. 1.

FIG. 3 is a rear view of the electronic device of FIG. 1.

FIG. 4 is a left side view of the electronic device of FIG. 1.

FIG. 5 is a right side view of the electronic device of FIG. 1.

FIG. 6 is a top view of the electronic device of FIG. 1.

FIG. 7 is a bottom view of the electronic device of FIG. 1; and,

FIG. 8 is a rear, left, perspective view of the electronic device of FIG. 1.

The features shown in broken lines form no part of the claimed design.

The lighter solid lines denote surfaces and contours. Line shading is not surface ornamentation.

1 Claim, 6 Drawing Sheets
